UNITED STATES PATENT OFFICE.

JAMES STEELE, OF GUELPH, CANADA, ASSIGNOR TO GEORGE SLEEMAN, OF SAME PLACE.

FENDER FOR STREET-CARS.

SPECIFICATION forming part of Letters Patent No. 587,880, dated August 10, 1897.

Application filed April 13, 1897. Serial No. 631,996. (No model.)

To all whom it may concern:

Be it known that I, JAMES STEELE, wire-worker, residing at the city of Guelph, in the county of Wellington and Province of Ontario, Canada, have invented a certain new and Improved Fender for Street-Cars, of which the following is a specification.

The object of my invention is to devise a simple and efficient fender for street-cars which, though normally raised to clear obstructions, may be dropped at any time to an operative position either by the motorman or by contact with an obstacle upon the track; and it consists, essentially, of a fender with an upward extension pivoted at the front of the car, links pivotally connecting the fender with bent levers, so constructed and pivoted below the end of the car that the pivot-point of each link upon the lever is normally below a line joining the pivot-point of the lever and the pivot-point of the link to the fender, and the latter thus held raised. To trip the device, a trigger-frame is slidingly supported upon the fender, so as to normally project in front of the same. The rear ends of the trigger-frame are pivoted to the bent levers, so that a blow upon the front end of the trigger-frame will rock the levers and draw back the links, so as to permit the fender to drop to the rail-level, the whole being constructed in detail substantially as hereinafter more specifically described, and then definitely claimed.

Figure 1 is a perspective view showing the end of a car provided with my improved fender dropped into operative position. Fig. 2 is a side elevation of the same, showing the fender in its normal position. Fig. 3 is a perspective detail of one of the lower bearings of the device.

In the drawings like letters of reference indicate corresponding parts in the different figures.

A is the fender, preferably formed of a suitable frame B, covered with netting or canvas. The rear end of the frame B is turned upwardly and is held within the jaws C, connected to the front of the car. These jaws are provided with suitable pins *a*, adapted to retain the frame in position.

D is a cross-bar connecting the opposite

sides of the horizontal portion of the fender-frame.

E are bent levers rigidly connected to the cross-bar F, which is journaled in the brackets G, depending from the under side of the front end of the car. In order to hold this cross-bar in position so that it may be removed at any time, I slot each bracket G immediately in front of the bearing *b* for the bar and close 60 the slot by means of a sliding stop H, which may be lifted out at any time to release the cross-bar F. (See Fig. 3.)

I are links, each pivotally connected at *c* to one of the bent levers E and at *d* to the horizontal bar D. *e* is a pin located upon each of the bent levers E and adapted to come in contact with one of the links I, so as to limit the downward motion of the bent lever to which it is attached. This pin might also be connected to the bracket G below the link I. This position is shown in Fig. 2, where, the pivot *c* being below a line joining the pivot-point of the bent lever E and the pivot *d*, the weight of the fender tends to swing the bent lever still 75 farther downward. As the pin *e* prevents this, the parts retain the position shown. If, however, the bent levers be thrown backward, the fender will be permitted to drop into the position shown in Fig. 1 and will retain that 80 position till the fender is again swung forward and upward to draw the pivot-points into the position shown in Fig. 2. To aid the weight of the fender in causing the parts to assume the position in Fig. 1, I connect the horizontal 85 bar D with the cross-bar F by one or more coil-springs J, which are normally in a state of tension.

In order to trip the fender automatically when an obstacle is struck, I connect thereto 90 the trigger-frame K, the front of which normally projects beyond the front end of the fender. (See Fig. 2.) The rear ends of the side bars of this trigger-frame K are pivotally connected to the ends of the bent levers 95 E, and near their forward ends are adapted to slide in any suitable guides, such as L. As soon as an obstacle is struck the trigger-frame is pushed backward and rocks the bent levers E till each pivot-point *c* is above a line 100 joining the pivot-point of its bent lever and the corresponding pivot-point *c*. After that point

has been reached the tension of the springs and the weight of the fender insures the latter assuming the position shown in Fig. 1. The springs J also serve to retain the parts 5 in the position shown in Fig. 2 by preventing shaking and swaying. As it is desirable sometimes to trip the fender by hand, I connect the cord M by means of a clamp to the trigger-frame K and lead it through suitable 10 guides to a position within reach of the motorman. By pulling upon the cord when the parts are in the position shown in Fig. 2 the device may be tripped, and by pulling upon the cord when the parts are in the position 15 shown in Fig. 1 the fender may be drawn back to its raised position.

In order to protect from injury by the front of the car any person caught by the fender, I run a rubber-covered guard N from side to 20 side of the fender near its upper end. This may be of any desired construction to effect the purpose.

If it be desired to shift the fender from one end of the car to the other, it is merely necessary to remove the sliding blocks H and the pins a, when the fender may be lifted from 25 its bearings. The cord M must also be disconnected. As each end of the car will be provided with similar bearings, the fender 30 may then be rapidly placed in position at the other end of the car.

From the above description it will be seen that I have devised a simple and efficient fender for street-cars which, though normally 35 raised to clear obstructions, may be dropped at any time to an operative position either by the motorman or by contact with an obstacle on the track.

It will also be seen that I have constructed 40 an automatic fender which may be quickly lifted from one end of the car to the other, which is a feature of value on many small lines where provision is not made for running the cars always with the same end foremost.

45 What I claim as my invention is—

1. In a device of the class described, a fender having one of its ends pivotally connected with the front of a car, in combination with a toggle-joint connection arranged to occupy 50 two positions and having one end connected with the car and its other end to the fender, the three pivots of the said toggle-joint being arranged substantially in line when in one of said positions to support the fender raised, and means operated by an obstacle for throwing 55 the toggle to its other position, thus allowing the fender to fall, substantially as described.

2. In a device of the class described, a fender 60 having one of its ends pivotally connected with the front of a car, in combination with a toggle-joint connection arranged to occupy two positions, a stop coacting with said toggle-joint connection when in one position to 65 support the fender raised, and means adapted to be operated by contact with an obstacle and arranged when operated to move said

toggle-joint connection to its other position, thus allowing said fender to drop until it strikes the ground or rails, substantially as 70 described.

3. In a device of the class described, a fender having a pivotal connection with a car, a toggle-joint connection arranged when in one position to support said fender with its front 75 end raised and when in another position to allow said front end to drop, and a slidingly-supported trigger-frame adapted to be operated by contact with an obstacle and arranged when operated to move said toggle-joint connection, thus allowing the front end of 80 said fender to drop, substantially as described.

4. In a device of the class described, a fender pivoted at its rear end to the front of a car, in combination with a lever pivoted below the 85 end of the car; a link pivoted at one end to the said lever and at the other to the fender below its pivot-point upon the car; and a stop so connected as to engage with the link when the pivot-point of the latter on the said lever 90 is below the line joining its pivot-point on the fender with the pivot-point of the lever, and thus retain the fender in its normal raised position, substantially as and for the purpose specified. 95

5. In a device of the class described, a fender pivoted at its rear end to the front of a car, in combination with a lever pivoted below the end of the car; a link pivoted at one end to the said lever and at the other to the fender 100 below its pivot-point upon the car; a stop so connected as to engage with the link when the pivot-point of the latter on the said lever 105 is below the line joining its pivot-point on the fender with the pivot-point of the lever and thus retain the fender in its normal raised position, and a trigger-frame slidingly supported by the fender with its front end projecting beyond the front of the same, and its rear end pivoted to the said lever above the pivot-point of the link, substantially as and for the purpose specified. 110

6. In a device of the class described, a fender pivoted at its rear end to the front of a car, in combination with a lever pivoted below the 115 end of the car; a link pivoted at one end to the said lever and at the other to the fender below its pivot-point upon the car; a stop so connected as to engage with the link when the pivot-point of the latter on the said lever is 120 below the line joining its pivot-point on the fender with the pivot-point of the lever and thus retain the fender in its normal raised position, a trigger-frame slidingly supported by the fender with its front end projecting beyond the front of the same, and its rear end 125 pivoted to the said lever above the pivot-point of the link, and a spring connected directly or indirectly with the car and to the fender so as to tend to draw the latter down 130 to its operative position.

7. In a device of the class described, a fender pivoted at its rear end to the front of a car, in combination with a lever pivoted below the

end of the car; a link pivoted at one end of the said lever and at the other to the fender below its pivot-point upon the car; a stop so connected as to engage with the link when the 5 pivot-point of the latter on the said lever is below the line joining its pivot-point on the fender with the pivot-point of the lever and thus retain the fender in its normal position, and a spring connected directly or indirectly 10 with the car and to the fender, so as to tend to draw the latter down to its operative position, substantially as and for the purpose specified.

8. In a device of the class described, the fender A, having its rear end turned upwardly 15 and pivotally connected to the front end of a car, in combination with the bent levers E, connected by the bar F, journaled in the brackets G; the links I, pivoted at d, to the fender A, and at c, to the bent levers E; the pin or stop e, 20 and the trigger-frame K, slidingly supported on the fender and pivoted at its rear end to the bent levers E, substantially as and for the purpose specified.

9. In a device of the class described, the 25 fender A, having its rear end turned upwardly and pivotally connected to the front end of a car, in combination with the bent levers E, connected by the bar F, journaled in the bracket G; the links I, pivoted at d, to the 30 fender A, and at c, to the bent levers E; the pin or stop e; the trigger-frame K, slidingly supported on the fender and pivoted at its rear end to the bent levers E; and the cord M, connected to the trigger-frame K, at such 35 a point as to serve both to trip and set the fender, substantially as and for the purpose specified.

10. In a device of the class described, the fender A, having its rear end turned upwardly 40 and pivotally and removably connected to the front end of a car, in combination with the

bent levers E, connected by the bar F, removably journaled in the brackets G; the links I, pivoted at d, to the fender A, and at c to the bent levers E; the pin or stop e; and 45 the trigger-frame K, slidingly supported on the fender and pivoted at its rear end to the bent levers E, substantially as and for the purpose specified.

11. In a device of the class described, the 50 fender A, having its rear end turned upwardly and pivotally and removably connected to the front end of a car, the combination with the bent levers E, connected by the bar F, removably journaled in the brackets G; the 55 links I, pivoted at d, to the fender A, and at c, to the bent levers E; the pin or stop e; the trigger-frame K, slidingly supported on the fender and pivoted at its rear end to the bent levers E, and a rubber-covered guard extending from side to side of the fender in front of the car end, substantially as and for the purpose specified. 60

12. In a device of the class described, the 65 fender A, having its rear end turned upwardly and pivotally connected to the front end of a car, in combination with the bent levers E, connected by the bar F, journaled in the brackets G; the links I, pivoted at d, to the fender A, and at c, to the bent levers E; the 70 pin or stop e, the trigger-frame K slidingly supported on the fender and pivoted at its rear end to the bent levers E; and a tension spring or springs connecting the bar F, with the fender, substantially as and for the purpose specified. 75

Guelph, April 8, 1897.

JAMES STEELE.
